UNITED STATES PATENT OFFICE.

GEORGE J. NETH, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed July 24, 1925. Serial No. 45,765.

My invention relates to autographic registers.

It is my object to provide an autographic register which has for its purpose the ejecting of a plurality of sheets, the winding of a record roll, and the aligning of said sheets for a new writing operation.

In particular my invention has for its object the ejecting of the upper sheets which are not to be kept as a record by means of winding on a drum and the simultaneous winding of the record sheet on a record roll and the aligning of the record sheet and the ejected sheets at the end of the ejecting operation.

In particular it is my object to provide an autographic register which has the following steps in its operation for the continuous movement of an operating handle: the holding in clamped aligned position of the sheets during the writing operation; the releasing of the clamp, the winding of the sheets on the ejecting drum and the record roll, the withdrawal of the aligning means during this operation, the unrolling of the ejecting roll to free the ejected sheets and leave them in condition for being torn off; the reestablishment of the clamping engagement between the clamping plate and the ejecting drum; and the simultaneous reciprocation of the ejecting drum and aligning pins to cause the pins to align the sheets before the sheets are clamped over the pins against the ejecting drum; and the causing of a slack portion to be formed in the record sheet prior to its final winding at the end of a cycle of operations on the record roll.

In addition to the foregoing objects, I have various detail objects such as the provision of the cutting plate on the ejecting drum, the provision of disappearing aligning pins within the ejecting drum so that the pins remain in engagement with the paper to move it until the wrapping operation starts, and the engaging knife portions on the ejecting drum engage the paper, and the provision of a record roll mechanism with the winding type of ejecting mechanism.

Referring to the drawings,

Figure 1 is a plan view of the register with the forward cover removed;

Figure 2 is a side elevation of the forward end of the register;

Figure 3 is a section on the line 3—3 of Figure 1;

Figure 4 is a section on the line 4—4 of Figure 1;

Figure 5 is a section on the line 5—5 of Figure 1;

Figure 6 is a section on the line 6—6 of Figure 1;

Figure 7 is a section on the line 7—7 of Figure 1. This figure shows the position of the parts during the winding operation.

Figure 8 is a section on the line 7—7 of Figure 1, both views 7 and 8 being taken on the same section line but in different positions; Figure 8 shows the parts in position at the end of the cycle of operations during the writing operation.

Figure 9 is a detail view showing the ejecting drum, and buffer mechanism; and is taken on the line 9—9 of Figure 1; and

Figure 10 is a section on the line 10—10 of Figure 3, showing the record roll clutch mechanism.

Referring to the drawings in detail, 1 is the bottom of a register, 2 is the rear wall and 3 the front wall. 4 designates the side walls. Journalled in the side walls are the usual spindles 5 carrying the rolls of paper 6. These rolls of paper consist of strips of paper wound upon the cores 7 mounted on the spindles. 8 and 9 designate the strips which are ejected and 10 designates the record strip. These strips pass upwardly over the guide rollers or bars 11 and thence over the writing table 12 where they are interleaved with the usual carbon sheets which are conventional in autographic registers.

They pass beneath the cover 13 which is hinged to the side walls at the rear thereof as at 14. This cover is provided with a writing opening 15. It is held in position at its forward end by the depending hooks 16 which depend from it. These hooks are engaged by fingers 17 with hooked ends 18.

The fingers 17 are mounted on the shaft 19 which is journalled in the side walls of the register. The fingers 17 are pressed in the operating or hooked position by the spring 20, one end of which is connected to the shaft 19 or to the fingers 17 if preferred and the other end is hooked about a stop 21 carried on the register side walls. The sheets are carried forwardly from the writing table 19 which has its forward end turned down at 22 over the clamping plate 23 beneath the ejecting drum 24. This clamping plate carries on its forward end a separating rod 25 spaced above the plate 23 so that the record sheet may pass beneath the plate and the two sheets to be ejected will pass over it. This ejecting plate 23 is mounted at one end upon a vertical reciprocating plate 26 which reciprocates in the guide ways or guide casing 27. This casing is mounted on the register by the bolts or screws 28. One side of the casing is provided with a slot 29 for the insertion of the finger 30 on one arm of the jaw 31 which is carried on the end of the reciprocating lever 32. This finger 30 fits in a slot 33 cut in the side of the plate 26. The inside of the plate 26 is provided with a right-angled extension 34 for supporting the clamping plate 23. It is also provided with an arcuate supporting arm lower down which supports the clamping plate further in towards the center of the register. This arcuate supporting arm is designated 35. The clamping plate is provided with spaced apertures 36 for receiving the reciprocating aligning pins 37.

Returning to the lever 32, it will be noted that the other arm of the jaw 38 is provided with a downwardly extending end 39 terminating in a shoe 40 which rides upon a cam 41 so that the lever is moved upwardly and downwardly at its jaw end and the jaw and lever 32 are also reciprocated. The purpose of this combined movement of reciprocation and vertical movement is to move the plate 26 with its clamping plate 23 vertically to clamping position and then release it by moving the lever 32 off of the cam 41.

In order to insure the dropping of the clamping plate when this is done a spring 42 is hooked to the plate at 43 and to the side wall of the register at the other end at 44. The arms 34 and 35 work in a slot 45 in the register side wall 4.

The rear end of the lever 32 is provided with a slot 46 in which is located a pin 47 carried by the side wall of the register. This guides this end of the lever 32 in its reciprocatory movement. The lever 32 is drawn backwardly by the action of the cam 41 against the tension of the spring 48, one end of which is secured to the lever 32 at 49 and the other end to the frame at 50.

The extensions 51 and 52 ride upon ex-

tensions of corresponding size 53 and 53 on the register side wall to provide a broad bearing and guiding surface to keep the lever in vertical alignment. The end of the lever is engaged by a reciprocating pin 55 working in the slot 56 in the register. This pin is carried by a lever 57 pivoted on the register side wall at 58 and spring-pressed by the spring 57. The lever is connected by a link 59 pivoted thereto at one end to a lever 60 at the other. This lever 60 is mounted on the transverse shaft 61 which is journalled in the side wall of the register and carries on its outer end the oscillating handle stop 62, which is provided with a depending finger piece 63 so that the stop may be moved out of the path of the handle and the shaft may be rotated to in turn move the pin 55 to push the member 32 forwardly so that the shoe 40 will drop off of the cam 41 as will be hereinafter explained. The movable finger piece 62 is limited in its movement in any one direction by the stop 64. The cam 41 is mounted on the handle shaft 65 operated by the handle 65. This handle shaft carries a ratchet wheel 66 and on the ratchet wheel a segmental gear 67 which is adapted to mesh with a gear 68 mounted on the ejecting drum shaft 69. This shaft is journalled in the ears 70 projecting from the side walls of the frame. On this shaft is carried the projecting arm 71 which is successively engaged by the projecting pins 72, 73, 74 and 75 which serve to move the shaft 69 slightly and to in turn move the pins 37 back and forth to cause them to enter the sheets more readily and to align the sheets just prior to the clamping operation. The pawl 76 engages with the teeth of the ratchet wheel 66 and is maintained in engagement by the weight 77. This pawl is pivoted on the side wall as at 78. This prevents backward movement of the register. Near this point is provided a stop 79 for limiting the downward movement of the plate 26. On the outside of the register at this point will be seen the end of the shaft 80 which carries a handle 81 so that the shaft may be operated. This shaft has cut away portions in it as at 82 so that the spreader arms 83 which ride thereon may be alternately lowered and elevated for the purpose of spreading the knurled rollers 84 and 85 between which the record web passes on its way to the record roll. These rollers are journalled in the side walls of the frame. The spreader arms consist of a pair of jaws mounted at either end of studs 86, the lower portion of the arms riding on the shaft 80 and the upper arm projecting between the rollers for the purpose of lifting the upper roller to spread the rollers. On the lower roller is the gear 87 and on the upper roller is a gear 88. The gear 87 on the lower roller is actuated by 130

the train of gears consisting of gears 88^a, 89, and 90 which are all supported on an arm 91, one end of which is pivotally mounted on the roller shaft of the lower roller 85 and the other end of which is provided with an arcuate annular extension 92 in which there is a slot 93 through which is projected a setting screw 94 for positioning the gear 90 with respect to the mutilated gear 95 mounted on the handle shaft 65. This gear 90 is engaged by a pawl 96 pivoted at 97 on the lever 91. The pawl is kept in engagement with the gear by the spring 98, one end of which engages with the pawl 96 and the other against a stop 99 mounted on the lever 91. The spring is supported by a stud 100 on the lever 91. Thus it is possible for the machine to be adjusted for different lengths of bills by adjusting the size of the gears on the arm 91 and correspondingly adjusting the position of the lever 91 to accommodate the different sizes of the gears so that the gear 90 will mesh with the gear 95. This gear 95 is mutilated at 95^a to permit of a cessation of movement of the pulling rollers 84 and 85 at a time when the record roll sheet is being pulled to create a slack. 101 is a guide rod for guiding the record roll sheet. 102 is the record roll shaft which is operated by a train of gearing on the other side of the register consisting of gears 103, 104, 105, 106 and 106^a. This train of gearing is operated from a gear 107 secured to a shaft 107^a and corresponding to the gear 87 also secured to the shaft 107^a on the opposite side of the register, said shaft 107^a being mounted in the side walls 4.

A clutch is provided consisting of friction plates 104^a and 105^a between the gears 105 and 104. The gear 103 meshes with 104 and 105 meshes with 106. A spider 105^b holds the several parts in frictional engagement. The parts are mounted on the shaft 105^c on which is mounted a retaining nut 105^d. The details of this clutch form no part of this invention as they are set forth and claimed in my co-pending application Ser. No. 592,712.

In order to permit the aligning of the several sheets of paper a predetermined amount of slack is imparted to the record roll near the end of the cycle of operation through the following means: A slide 110 is mounted adjacent the side walls 4 in brackets 111. At the rear end of the slide and preferably formed integral therewith is a U-shaped bracket 109 having secured thereto a block 113 to form a stop, as will presently appear. This block is located on the inner side of the bracket member which lies in a plane sufficiently distant from the slide to afford space for the gear 95, said block lying in the path of travel of a finger 112 attached to the gear 95. The lower end of

this bracket member carries a rod 108 over which the record roll sheet is fed. Thus as the gear 95 is rotated the finger 112 will engage the block 113 and cause the bracket 109 and slide 110 to move toward the front 70 of the register, thereby moving the rod 108 in the same direction and causing a predetermined amount of slack in the web which is being wound on the record roll. When this is done the rack 114 on the slides 75 operates the pinions 115 on the shaft 116. This is resisted by the spring 117 which is connected at one end to the shaft at 118 and at its other end at 119 to the stops 120 carried by the side walls of the register. 80 This arrangement serves to return the rod after the actuating finger 112 passes by and the slack has been created.

A shield 121 is provided back of the rod 101 and the two rollers which pull the record sheet in order to facilitate the management of the sheet and placing of it between the rollers. The record sheet, before it passes to the record roll, passes over a guide bar 122 carried on arms 123 mounted in the 90 side walls of the register.

Turning to the ejecting means for the upper two sheets of paper, the ejecting drum 24 is rotated by the segmental gear 67 engaging with the gear 70 on the shaft supporting the ejecting drum. The machine is adjusted to different lengths of bills by adjusting the length of the segmental gear 67.

This drum carries two disappearing, reciprocating, aligning pins which are relatively long and tapered and are adapted at their maximum dimension to fit within the file punch apertures which are customarily 15 of an inch in diameter. These pins 37 move back and forth within the drum 24 which is a hollow member mounted on the solid ends 124. In this cylindrical space are located the guide ways 125 which fit within the apertures 126 within the pins. The pins are provided with stops 127 to limit the outward movement of the pins. The drum is wound with the paper on it by the segmental gear 67 against the resistance of a spring 128 which is connected at one end to the unwinding gear 129 and at its other end to a shaft 130 which is mounted in the side wall of the register. The spring 128 is wound on the shaft, which shaft also supports loosely the unwinding gear 129 which engages with a pinion 131 mounted on one end of the ejecting drum. Thus when the gears used for winding the drum become disengaged, the drum is released and the spring 128 operates to turn the drum backwardly.

In order to insure that the drum will turn to a position where the pins are depending downwardly over the apertures 36 and the clamping plate 23 a form of retaining stop is provided to overcome the possibility of 130

the drum and pins coming to rest with the pins to one side of the apertures 36, due to the violent reaction of the spring 128 in returning the drum. For this purpose an arm 132 is mounted on one end of the ejecting drum shaft and provided with a head 133 which is adapted to pass by a spring pressed trigger 134 while it is winding and to pass by the retaining hook 135 during the winding operation because the arm 132 is moving slowly. The finger 134 may move in one direction to permit the arm 132 to pass by. If 134 is moved backwardly in the other direction it will pull the hook 135 upwardly so that when the finger 132 violently taps 134 in its return movement it throws up the hook 135 to the rear of it and when it bounces back off of 134 the hook 135 catches it so that the drum is steadied in position to insure the pins being over the holes 36. Springs 136 and 137 actuate the respective fingers 134 and 135 which are pivoted at 138 on the side walls of the register.

25 In order to insure the paper remaining in engagement with the ejecting drum during the wrapping operation after the pins have been telescoped in the drum due to the winding of the paper on the drum, a plurality of relatively short and very sharp knife edges are provided on the surface of the drum between the pins preferably on either side of the pins. These knife edges are marked 139. The clamping plate 23 is 30 cut away at 140 to accommodate these knife edges.

Transversely arranged on the ejecting drum is a tearing off plate 141.

Method of operation.

Assuming the parts to be in the position where the sheets can be written upon, it will be observed that the handle 65^a is at rest against the stop 62. The clamping plate is in its uppermost position as in Figure 4 with the pins in the sheets of paper. In order to permit the handle to move the stop must be moved. This results in pushing the arm 32 forwardly through the medium of the shaft 61 and lever 60, link 59 and lever 57 and pin 55. This forward movement allows the arm 39 and shoe 40 to drop off of the cam as shown in dotted lines in Figure 6, and carry the plate 26 downwardly due to the action of the spring 42 thereof. The handle is then ready to turn as it now can clear the stop and as it does so the segmental gear 67 engages the gear 68 rotating the ejecting drum. The descent of the clamping plate having taken place with the descent of the plate 26 carried with it the record roll sheet which was thereby disengaged from the depending aligning pins, but the upper two sheets still remain on the pins as the paper is slightly

under tension and the sheets are held against the pins by the tension. As the drum turns the sheets are drawn over it because of their engagement with the telescoping aligning pins. As the drum makes a half revolution 70 the pins fall downwardly due to the effect of gravity, telescoping within the ejecting drum, and in the meanwhile the small knife blades have penetrated the paper to hold it. The drum continues to rotate, wrapping the 75 paper around it for one or more revolutions depending upon the length of the sheets to be ejected, until the end of the segmental gear 67 is reached, at which time the ejecting drum is released and allowed to 80 unwind due to the action of the spring 128. Thus the sheets are unwound and are allowed to unwind in ejected condition and the ejecting roller is returned to initial position with the aligning pins depending 85 from it over the new apertures in the sheets. In the meanwhile the record sheet has been moved forward a length and the new apertures in the sheet are in position over the apertures in the plate beneath the aligning pins. The buffer member prevents the overrun of the ejecting drum so that the pins are left in depending position substantially vertically over the new holes in the paper. The cam 41 then begins to lift the arm 38 90 and as it does so it lifts the plate 26 and the clamping plate 23 so that the record sheet and the upper sheets will be forced over the ends of the aligning pins. As this is taking place, the pins are moved back and forth 95 with the ejecting drum by reason of the successive tapping of the pins 71 by the projecting pins 72, 73, 74 and 75, thus assisting the pins in entering the sheets and aligning the sheets. Just at this time when the plate is traveling to its uppermost position to finish the clamping operation and the aligning operation, the bar 108 is being moved forwardly to create a slack in a record roll. During this period the gear 90 is opposite the mutilated gear portion 95^a of the gear 95 so that the rollers 84 and 85 are not operative. After the slack has been created 100 the rollers pull the record roll sheet due to the continued movement of the handle to a 105 stop position.

It will therefore be observed that starting with the writing position we have the following sequence of operations: the rotation of the ejecting drum winding the sheets thereon, the disappearance of the aligning pins, the further winding of the sheets, the release of the ejecting drum and the unwinding of the ejected sheets, the positioning of the pins which have now reappeared over the new holes in the paper, the lifting of the record roll sheet on the clamping plate, the movement of the pins and ejecting drum back and forth to facilitate the entry of the pins and the forcing of the paper up 122 123 133

wardly so that the pins will enter the new holes and align the sheets and at the same time the formation of a slack in the record roll sheet, the winding of which is tempor-
5 rarily suspended and resumed during the end of the stroke during the final rolling and aligning operation.

It will be understood that I desire to comprehend within my invention such modifications as may be necessary to adapt it to varying conditions and uses.

Having thus fully described my invention, what I claim as new and desire to secure by Letters Patent, is:-

15 1. In an autographic register, an actuating means, and ejecting drum, means to rotate said ejecting drum from the actuating means to wind about said drum sheets carried in the register, aligning pins carried by said 20 drum engaging with apertures in sheets carried in the register, said aligning means adapted to disappear within the drum as the winding takes place, means to release said ejecting drum and to unwind it and the 25 sheets wound thereon.

2. In an autographic register, an actuating means, an ejecting drum, means to rotate said ejecting drum from the actuating means to wind about said drum sheets carried in the register, aligning pins carried by said 30 drum engaging with apertures in sheets carried to the register, said aligning means adapted to disappear within the drum as the winding takes place, means to release said 35 ejecting drum and to unwind it and the sheets wound thereon, and means to cause the aligning pins to reappear and means to move the paper sheets against the pins for a re-aligning of the sheets for the entrance of the pins in the apertures in the paper.

40 3. In an autographic register, an actuating means, an ejecting drum, means to rotate said ejecting drum from the actuating means to wind about said drum sheets carried in the register, aligning pins carried by said 45 drum engaging with apertures in sheets carried to the register, said aligning means adapted to disappear within the drum as the winding takes place, means to release said 50 ejecting drum and to unwind it and the sheets wound thereon, means to cause the aligning pins to reappear and means to move the paper sheets against the pins for a re-aligning of the sheets for the entrance of the pins in the apertures in the paper, and a plurality of knife members on said ejecting drum for engaging and holding the paper sheets.

55 4. In an autographic register, an actuating means, an ejecting drum, means to rotate said ejecting drum from the actuating means to wind about said drum sheets carried in the register, aligning pins carried by said 60 drum engaging with apertures in sheets carried to the register, said aligning

means adapted to disappear within the drum as the winding takes place, means to release said ejecting drum and to unwind it and the sheets wound thereon, means to cause the aligning pins to reappear and means to move the paper sheets against the pins for a realigning of the sheets for the entrance of the pins in the apertures in the paper, and means for preventing the ejecting drum to unwind too far at the end of its unwinding 75 operation.

5. In an autographic register having a plurality of sheets with spaced apertures, an actuating means, an ejecting drum actuated thereby, a plurality of telescoping pins 80 carried by said drum adapted to move outwardly from the drum due to the effect of gravity and to disappear for a like cause, a clamping plate beneath the paper sheets, means to maintain the record sheet on the plate, said plate having apertures for receiving said pins, means to move said plate upwardly and downwardly, means to return the ejecting drum to its initial position after it has been actuated, and means 90 to store the record roll sheet.

6. In an autographic register having a plurality of sheets with spaced apertures, an actuating means and an ejecting drum actuated thereby, a plurality of telescoping 95 pins carried by said drum adapted to move outwardly from the drum due to the effect of gravity and to disappear for a like cause, a clamping plate beneath the paper sheets, means to maintain the record sheet on the plate, said plate having apertures for receiving said pins, means to move said plate upwardly and downwardly, means to return the ejecting drum to its initial position after it has been actuated, means to store the 100 record roll sheet, and means to prevent the overrun of the ejecting roll during the unwinding operation.

7. In an autographic register having a plurality of sheets with spaced apertures, 110 an actuating means and an ejecting drum actuated thereby, a plurality of telescoping pins carried by said drum adapted to move outwardly from the drum due to the effect of gravity and to disappear for a like clause, a clamping plate beneath the paper sheets, means to maintain the record sheet on the plate, said plate having apertures for receiving said pins, means to move said plate upwardly and downwardly, means to return the ejecting drum to its initial position after it has been actuated, means to store the record roll sheet, means to prevent the overrun of the ejecting roll during the unwinding 115 operation, and means to form a slack in the record roll and to simultaneously temporarily discontinue the winding of the record roll sheet.

8. In an autographic register having a plurality of paper sheets with spaced aper- 120

- tures, an actuating handle, a movable stop therefor, an ejecting drum, means connected to the handle for rotating the drum in one direction to wind about said drum paper sheets carried in said register, means rotated by the drum for yieldingly resisting this rotation and for unwinding it when it has been released from the winding means, a clamping plate, means to raise and lower said clamping plate, the lowering means being controlled by the movable stop and the elevating means being controlled by the handle, and a plurality of telescoping pins carried by said ejecting drum.
15. In an autographic register having a plurality of paper sheets with spaced apertures, an actuating handle, a movable stop therefor, an ejecting drum, means connected to the handle for rotating the drum in one direction to wind about said drum paper sheets carried in said register, means rotated by the drum for yieldingly resisting this rotation and for unwinding it when it has been released from the winding means, a clamping plate, means to raise and lower said clamping plate, the lowering means being controlled by the movable stop and the elevating means being controlled by the handle, a plurality of telescoping pins carried by said ejecting drum, and means for preventing said ejecting drum from overrunning its final position upon unwinding.
10. In an autographic register having a plurality of paper sheets with spaced apertures, an actuating handle, a movable stop therefor, an ejecting drum, means connected to the handle for rotating the drum in one direction to wind about said drum paper sheets carried in said register, means rotated by the drum for yieldingly resisting this rotation and for unwinding it when it has been released from the winding means, a clamping plate, means to raise and lower said clamping plate, the lowering means being controlled by the movable stop and the elevating means being controlled by the handle, a plurality of telescoping pins carried by said ejecting drum, means for preventing said ejecting drum from overrunning its final position upon unwinding, means driven from said handle for winding a record roll sheet, means to carry the record roll sheet upwardly and downwardly with the clamping plate, means to form a slack in said sheet during the cycle of operations and to temporarily discontinue the winding of the record roll sheet during the formation of the slack.
11. In an autographic register having a plurality of sheets with spaced apertures, an actuating means, an ejecting drum, means for winding sheets about said drum, telescoping pins mounted therein, a tearing off plate carried thereon, yielding means to resist the winding of the drum and to unwind it upon its release from the winding means.
12. In an autographic register having a plurality of sheets with spaced apertures, an operating handle, a movable stop, a ratchet and pawl to prevent the handle moving backward, a segmental gear connected to said handle, an ejecting drum adapted to be driven by said segmental gear to wind about said drum sheets carried in said register, telescoping pins carried thereby, a cut off plate carried thereby, a clamping plate, means connected with the handle for elevating said clamping plate, means connected with said handle for disconnecting the elevating means for the plate allowing it to descend, means on the plate for separating one of the sheets from the other sheets, said plate having apertures for receiving said telescoping pins, means to resist the winding of the ejecting drum and adapted to unwind it when the winding means ceases to operate, means associated with said handle for reciprocating said drum and pins after the drum has unwound to facilitate the entry of the pins into the apertures in the paper.
13. In an autographic register having a plurality of sheets with spaced apertures, an operating handle, a movable stop, a ratchet and pawl to prevent the handle moving backward, a segmental gear connected to said handle, an ejecting drum adapted to be driven by said segmental gear to wind about said drum sheets carried in said register, telescoping pins carried thereby, a cut off plate carried thereby, a clamping plate, means connected with the handle for elevating said clamping plate, means connected with said handle for disconnecting the elevating means for the plate allowing it to descend, means on the plate for separating one of the sheets from the other sheets, said plate having apertures for receiving said telescoping pins, means to resist the winding of the ejecting drum and adapted to unwind it when the winding means ceases to operate, means associated with said handle for reciprocating said drum, and pins after the drum has unwound to facilitate the entry of the pins into the apertures in the paper, and means for winding a record roll sheet actuated by said handle.
14. In an autographic register having a plurality of sheets with spaced apertures, an operating handle, a movable stop, a ratchet and pawl to prevent the handle moving backward, a segmental gear connected to said handle, an ejecting drum adapted to be driven by said segmental gear to wind about said drum sheets carried in said register, telescoping pins carried thereby, a cut off plate carried thereby, a clamping plate, means connected with the handle for elevating said clamping plate, means connected with said handle for disconnecting the elevating means for the plate allowing it to

descend, means on the plate for separating one of the sheets from the other sheets, said plate having apertures for receiving said telescoping pins, means to resist the winding of the ejecting drum and adapted to unwind it when the winding means ceases to operate, means associated with said handle for reciprocating said drum, and pins after the drum has unwound to facilitate the entry of the pins into the apertures in the paper, and means for winding a record roll sheet actuated by said handle, and means actuated by said handle adapted to form a slack in the record sheet and to temporarily disconnect the winding of the sheet during the formation of the slack, and means to permit the record roll to slip as the size of the roll increases to maintain a uniform tension on the sheet, and means to prevent an overrun during unwinding of the ejecting drum.

15. In an autographic register having a plurality of sheets having spaced apertures, a handle, a handle shaft, a cam carried thereon, a lever pivoted on the register having spaced jaws, one of which is adapted to ride on said cam and the other of which is adapted to move vertically, a supporting plate, a clamping plate supported thereby, an ejecting drum, means on said handle for actuating said ejecting drum to wind thereon sheets carried in said register, telescoping pins therein, yielding means to resist the rotation of said drum during its winding operation, means connecting the drum to said yielding means adapted to cooperate in unwinding said drum when it is released from the winding means, and means on said winding drum adapted to be successively moved a portion of a revolution and then returned by said yielding means, and means for successively engaging with said last mentioned means to oscillate said pins so that they may readily enter the apertures in the sheets of paper.

17. In an autographic register having a plurality of sheets having spaced apertures, a handle, a handle shaft, a segmental gear detachably mounted thereon, a rotating 65 ejecting drum, a pinion thereon meshing with said segmental gear to rotate said drum to wind about it sheets carried in said register, a plurality of telescoping pins carried by said drum, a cut off plate carried 70 thereby, a clamping plate, means for raising and lowering said clamping plate, means for unwinding said drum when the winding operation is finished, a movable stop for limiting the movement of said handle, and means connected with said stop for controlling the raising and lowering of said clamping plate, said stop being used when actuated for permitting the descent of the plate prior to the rotation of the handle.

16. In an autographic register having a plurality of sheets having spaced apertures, a handle, a handle shaft, a cam carried thereon, a lever pivoted on the register having

spaced jaws, one of which is adapted to ride on said cam and the other of which is adapted to move vertically, a supporting plate, a clamping plate supported thereby, 45 an ejecting drum, means on said handle for actuating said ejecting drum to wind thereon sheets carried in said register, telescoping pins therein, yielding means to resist the rotation of said drum during its winding 50 operation, means connecting the drum to said yielding means adapted to cooperate in unwinding said drum when it is released from the winding means, and means on said winding drum adapted to be successively 55 moved a portion of a revolution and then returned by said yielding means, and means for successively engaging with said last mentioned means to oscillate said pins so that they may readily enter the apertures 60 in the sheets of paper.

17. In an autographic register having a plurality of sheets having spaced apertures, a handle, a handle shaft, a segmental gear detachably mounted thereon, a rotating 65 ejecting drum, a pinion thereon meshing with said segmental gear to rotate said drum to wind about it sheets carried in said register, a plurality of telescoping pins carried by said drum, a cut off plate carried 70 thereby, a clamping plate, means for raising and lowering said clamping plate, means for unwinding said drum when the winding operation is finished, a movable stop for limiting the movement of said handle, and means connected with said stop for controlling the raising and lowering of said clamping plate, said stop being used when actuated for permitting the descent of the plate prior to the rotation of the handle.

In testimony whereof, I affix my signature.

GEORGE J. NETH.
